UNITED STATES PATENT OFFICE.

WILLIAM D. SCOTT, OF NEW YORK, N. Y.

DESIGN FOR A CARAFE.

44,982.

Specification for Design.

Patented Dec. 2, 1913.

Application filed July 24, 1911. Serial No. 640,366. Term of patent 7 years.

To all whom it may concern:

Be it known that I, WILLIAM D. SCOTT, a citizen of the United States, residing in the city of New York, borough of Brooklyn, county of Kings, and State of New York, have invented a new, original, and ornamental Design for Carafes, of which the following is a specification, reference being had to the accompanying drawing, forming part thereof.

I claim:

The ornamental design for a carafe, as shown.

WILLIAM D. SCOTT.

Witnesses:

CHAS. LYON RUSSELL,
WM. C. DUNN.
